Primary Examiner — T Chase Nelson*Assistant Examiner* — Sydney Margaret Parsley(74) *Attorney, Agent, or Firm* — Dilworth & Barrese, LLP(57) **CLAIM**

The ornamental design for a foundation block, as shown and described.

DESCRIPTION

FIG. 1 is a top perspective view of a foundation block showing our new design;

FIG. 2 is a top plan view thereof;

FIG. 3 is a bottom perspective view thereof;

FIG. 4 is a side elevational view thereof;

FIG. 5 is a sectional view thereof along the line 5-5 of FIG. 4;

FIG. 6 is a front elevational view thereof; and,

FIG. 7 is a sectional view thereof along the line 7-7 of FIG. 6.

The broken lines depict the sectional view indicators and form no part of the claimed design.

1 Claim, 5 Drawing Sheets---
